UNITED STATES PATENT OFFICE.

HENRY S. AYLING, OF DANVILLE, ILLINOIS, ASSIGNOR OF ONE-HALF TO ARTHUR J. WILMOT, OF DANVILLE, ILLINOIS.

SMOKE-CONSUMER.

1,190,843.

Specification of Letters Patent. Patented July 11, 1916.

Application filed September 9, 1915. Serial No. 49,761.

To all whom it may concern:

Be it known that I, HENRY S. AYLING, a citizen of the United States, and a resident of Danville, in the county of Vermilion and State of Illinois, have invented a new and Improved Smoke-Consumer, of which the following is a full, clear, and exact description.

One object of the invention is to provide 10 a new and improved smoke consumer for the use of locomotive furnaces and other furnaces using coal, oil, wood or other fuel, and arranged to insure complete combustion of the burning fuel and to greatly economize 15 in the amount of the fuel employed.

Another object is to increase the efficiency 20 of the engine by a quick generation of steam, increase in the steam pressure and enlargement of the exhaust nozzle of a locomotive.

25 In order to produce the desired result, use is made of pipes having portions perforated on the under side and extending within the fire box of the boiler immediately above the burning fuel on the grate of the fire box, 30 the terminals of the pipes opening into the atmosphere to allow air to pass into the pipes to be heated therein and to issue through the perforated portions to mix with the gases arising from the burning fuel in 35 the fire box. Use is also made of diaphragms in the pipes above the perforations to cause the air to travel over the diaphragms to be thoroughly heated before reaching the perforated portions.

40 A practical embodiment of the invention is represented in the accompanying drawings forming a part of this specification, in which similar characters of reference indicate corresponding parts in all the views.

45 Figure 1 is a longitudinal central section of the fire box portion of a locomotive boiler provided with the smoke consumer; Fig. 2 is a cross section of the same on the line 2-3 looking in the forward direction of the arrow *y*; Fig. 3 is a similar view of the same on the line 2-3 looking rearward in the direction of the arrow *x*; Fig. 4 is an enlarged longitudinal central section of one 50 more particularly the construction of the diaphragms; and Fig. 5 is a cross section of the same on the line 5-5 of Fig. 4.

Within the fire box 10 of a steam boiler furnace 11 of any approved construction, 55 are arranged side air delivering pipes 12

extending along the sides of the fire box and immediately above the burning fuel on the grate 13 arranged within the fire box in the usual manner. The ends of each side air delivering pipe 12 connect with the air admission pipes 14 and 15 extending down through the bottom of the fire box to open into the atmosphere and thus allow the fresh air to pass through the pipes 14 and 15 into the pipes 12. The lower portions of 60 the pipes 12 are provided with perforations 16 and within each pipe 12 are arranged diaphragms 17 and 18 having their outer ends terminating in turned down flanges 19 (see Fig. 4) while their inner ends are 65 spaced apart. It will be noticed that the diaphragms 17 and 18 extend above the perforations 16 and the air entering the pipes 14, 15 passes over the diaphragms 17 and 18 to the middle of the pipe 12 which 70 then passes down under the diaphragms to the perforations 16 and out of the same into the gases arising from the burning of the fuel so that a highly inflammable mixture is 75 formed to consume the smoke and to utilize 80 approximately all the heat units contained in the burning fuel. Use is also made of top air delivering pipes 20 extending through the back of the fire box near the top thereof in a downward and forward direction to 85 pass through the front wall of the fire box, as plainly indicated in Fig. 1. The pipe 20 has the lower forward portion provided with perforations 21 and diaphragms 90 similar to the diaphragms 17 and 18 are 95 preferably arranged in the pipes 20. It will be noticed that the pipes 20 deliver fresh air to the gases that pass upwardly and forwardly in the middle portion of the fire box so that such gases receive a full supply of 98 fresh air to insure complete combustion.

As a further aid to complete combustion air is delivered to the gases at the back and front of the fire box and for this purpose use is made of back air delivering pipes 22 100 and front air delivering pipes 23. The pipes 22 extend transversely at the back of the fire box 10 and their outer ends are closed by plugs 24 and the inner ends are connected with pipes 25 leading to the atmosphere to supply the said pipes 22 with fresh air, the lower portions of the pipes 22 being provided with perforations 26 similar to the perforations 16 and 21. The front air delivering pipes 23 extend transversely 105 110

at the forward side portion of the fire box 10 and the outer ends of the said pipes are closed by plugs 27, the inner ends being connected with an elbow or T 28 connected 5 by a pipe 29 with the atmosphere to supply pipes 23 with fresh air, the lower portions of the pipes 23 being provided with perforations 30 for conducting the air into the gases arising from the burning fuel at the 10 front of the fire box.

It will be noticed that by the system of pipes employed, a large amount of fresh air is passed into the fire box to mingle with the gases arising from the burning fuel to 15 insure complete combustion.

It is understood that the draft in the fire box causes the fresh heated air to be drawn through the perforations of the several air delivering pipes. It is also understood that 20 the perforations in each pipe have an aggregate area equal or somewhat in excess of the aggregate area of the ends of the air admission pipe.

Having thus described my invention, I 25 claim as new and desire to secure by Letters Patent:

1. A smoke consumer for furnaces, comprising air delivering pipes extending above the burning fuel in the fire box of the furnace, the air delivering pipes being provided 30 at their lower portions with perforations, the said air delivering pipes being connected at the ends with the atmosphere to admit air to the said air delivering pipes, and two 35 diaphragms extending lengthwise within each air supply pipe above the perforations, the diaphragms terminating short of each other near the middle of the pipe and the outer ends of the diaphragms being 40 turned down to cause the air passing into the ends of the pipe to travel over the diaphragms to the middle of the pipe and then pass between the adjacent ends of the diaphragms into the perforated portions of the 45 pipe out through the perforations into the fire box.

2. A smoke consumer for furnaces, comprising side air delivering pipes extending longitudinally within the fire box at the 50 sides thereof, the said side air delivering pipes being connected at their ends with the atmosphere and having their lower portions 55 perforated, and a plurality of top air delivering pipes extending longitudinally within the fire box from the back of the fire box in a downward and forward direction to the front of the same, the ends of each of the said top delivering pipes opening into

the atmosphere and the forward bottom portions of the said top delivering pipes being 60 perforate.

3. A smoke consumer for furnaces, comprising side air delivering pipes extending longitudinally within the fire box at the sides thereof, the said air delivering pipes 65 being connected at their ends with the atmosphere and having their lower portions perforated, top air delivering pipes extending longitudinally within the fire box in a downward and forward direction, the ends 70 of each of the said top delivering pipes opening into the atmosphere and the forward bottom portions of the said top delivering pipe being perforated, each side and top delivering pipe being provided with two 75 diaphragms having their outer ends engaging the pipe and their inner ends spaced apart near the middle of the pipe, and back air delivering pipes extending transversely in the fire box at the back thereof and above 80 the burning fuel in the fire box, the said back air delivering pipes having their bottom portions perforated.

4. A smoke consumer for furnaces, comprising side air delivering pipes extending 85 longitudinally within the fire box at the sides thereof, the said side air delivering pipes being each connected at its ends with the atmosphere and having its lower portions 90 perforated, top air delivering pipes extending longitudinally within the fire box in a downward and forward direction, the ends 95 of each of the said top delivering pipes opening into the atmosphere and the forward bottom portions of the said top delivering pipes being perforated, back air delivering 100 pipes extending transversely in the fire box at the back thereof and above the burning fuel in the fire box, the said back air delivering pipes being each connected at one end with the atmosphere and having its bottom portion perforated, and front air delivering pipes extending transversely in the fire box at the front end thereof and above the burning fuel in the fire box, the inner ends of 105 the said front air delivering pipes opening into the atmosphere through a common pipe and the bottom portions of the said front air delivering pipes being perforated.

In testimony whereof I have signed my 110 name to this specification in the presence of two subscribing witnesses.

HENRY S. AYLING.
